UNITED STATES PATENT OFFICE.

WILLIAM D. BROWN, OF INDIANAPOLIS, INDIANA, ASSIGNOR TO CHAMBERS,
BERING & QUINLAN, OF DECATUR, ILLINOIS.

IMPROVEMENT IN RING-BLANKS FOR SWINE.

Specification forming part of Letters Patent No. **205,996**, dated July 16, 1878; application filed April 29, 1878.

To all whom it may concern:

Be it known that I, WILLIAM D. BROWN, of Indianapolis, in the county of Marion and State of Indiana, have invented a new and useful Ring-Blank for Ringing Swine, of which the following is a description, reference being had to the accompanying drawings.

My invention relates to rings used in the snouts of swine.

The object of my invention is to construct a ring so that when one end passes through the flesh and gristle of a hog's nose the other end will remain stationary, and the end that passes through the snout will make a tight joint with the other end outside of the flesh, and both ends have a form that will prevent the joint from working inside of the wound.

My invention consists of the form and construction of the ring-blank, as will be herein-after set forth and described.

In the accompanying drawings my invention is illustrated by two figures, of which Figure 1 represents the blank in its proper form to be inserted in the jaws of a ringing-instrument; and Fig. 2 represents the ring closed, as it would appear after passing through the snout of a hog.

The ring-blank is made with a form like that shown in Fig. 1, the part *d* being perfectly straight and beveled at the extreme end *d*³. The part *d*¹ is curved, and the end *d*² for a short distance is straight, and also provided with a beveled end, *d*⁴, as shown. The ring-blank G is inserted in the jaws of an instrument that will hold the point *d*³ and straight part *d*, and prevent them from slipping. The curved part *d*¹ must fit in a curved jaw, so

that when the instrument is closed the point *d*⁴ will be forced forward and downward as the curved part *d*¹ is forced along the curved jaw of the instrument, and thus the point *d*⁴ is thrust through the flesh and gristle of the nose in a curved manner, while the point *d*³ remains at rest in the lower jaw until it comes in contact with the stationary point *d*³, where they are firmly pressed or squeezed together, leaving the curved part *d*¹ in the wound, and the joint outside of the wound, with two straight parts, *d*⁵ *d*⁵, Fig. 2, at each side of the joint to prevent the joint from working inside of the wound.

I am aware that various forms of rings have been used before, some of which close outside of the flesh and others inside of the nose, and to the form of ring-blanks shown in such devices I make no broad claim.

What I claim as new, and desire to secure by Letters Patent, is—

The ring-blank G, having two straight sides, *d* *d*², with beveled ends *d*³ *d*⁴, and a curved part, *d*¹, formed near the short straight end *d*², adapted to be bent and form a ring with two short straight sides, *d*⁵ *d*⁵, and a curved part, *d*¹, and form a joint at the extreme ends of the straight parts, in the manner and for the purpose set forth and described.

In testimony whereof I have signed my name to this specification in the presence of two subscribing witnesses.

WILLIAM D. BROWN.
